SEWING MACHINE PRESSER FOOT
CONSTRUCTION

Abraham Masler, Brooklyn, N. Y.

Application July 30, 1940, Serial No. 348,329

11 Claims. (Cl. 112—151)

The improvements relate to the presser foot of a sewing machine and attachments connected and operating therewith and are partly in the nature of improvements in the subject matter of my Patent No. 2,202,059, granted May 28, 1940.

The object of the present improvements are in part to provide a presser foot construction constructed and arranged to hold securely various devices to be used in cooperation therewith or as parts thereof; to so design these attachments and the presser foot that various operations may be performed or facilitated and better work on material of various character and thickness produced. Other objects and advantages will appear from the following description.

The improvements are illustrated in the accompanying drawings, referred to herein, and in which—

Fig. 1 is a side elevation of an exemplary embodiment;

Fig. 2 a front view thereof;

Fig. 3 is a vertical medial section substantially on the line 3—3 of Fig. 2;

Fig. 4 a side elevation and Fig. 5 a plan of a two part presser foot assembled;

Fig. 6 is a side elevation and Fig. 7 an enlarged detail of a detachable foot member secured to the post of the foot in different manner from that of Figs. 1 to 5, Fig. 6 showing the lower portion of the post and the method of attaching the member;

Fig. 8 is a front view of an adjustable guide member or runner adapted to be used in combination with cloth guiding and holding members of different widths, said guide mounted on the post;

Fig. 9 is a plan of one of the detachable holders and guides with presser foot member secured thereto and Fig. 10 is a side elevation thereof;

Fig. 11 is a plan of the detachable runner of Fig. 8 with its mounting and adjusting members; and

Fig. 12 is a side view thereof;

Fig. 13 is a side view of a tape or ribbon guide and tension device on the presser foot, and Figs. 14 and 15 are plan and front views respectively of this device;

Fig. 16 is a plan and Fig. 17 a side view of a double cloth holding and guiding device adapted to extend laterally on either or both sides of the presser foot.

It will be understood that the guides and runners may be made left handed instead of right handed, as shown, so that if desired they will operate on the cloth at the left side of the presser

foot instead of the right. This is desirable in cases where the nap of the cloth or the peculiar character and weight of the cloth makes it advisable.

5 In the drawings, 1 represents a presser foot shank adapted to be mounted on the lower portion of an ordinary presser bar and 2 the presser foot member integral therewith. This unit is shaped, bored and threaded to carry the detachable members hereinafter described, by having a cross recess 3 at the horizontal base of the foot, a hole 4 extending crosswise through the upright portion of the shank member with a flat side next to the internally threaded bore 5 running thereinto, an inclined internally threaded bore 6 running through the heel of member 1 from back to front and a threaded recess 7 above the bore 5.

The cross recess 3 is angular and is adapted to 20 receive and hold the shanks 23 of the detachable members, which are held therein by the bottom horizontally turned portion 10 of the slide 9 secured to the shank member by the set screw 11 passing through the slot 12 and into the recess

25 7. A slot 13 through which the set screw 14 extends into the bore 5 and to the hole 4 together with the slot 12 permits the member 9 to slide up and down when the screw 11 is loosened, and the slots hold this member against lateral movement by engaging the screws. The slide 9, also holds the vertical plate 15 between it and the front face of the shank member 1, and this plate extends slightly below the horizontally turned bottom of the slide and into contact with the shank of the removable member, where it is provided with a beveled bottom 16. The thumb screw 17 extending through the inclined bore 6 when tightened presses against the lower end of the plate 15 and causes the inclined terminus of

30 35 the plate to move and wedge against the shank 28 of the detachable member, thereby securely binding the said shank in the recess 3. In this manner the detachable parts are securely held in position by a turn of the set screw 17 and released by a turn in the opposite direction.

The set screw 14 not only serves to align the slide 9 but extending through the bore 5 to the flat sided hole 4 engages members such as the flat sided shank 19 of the detachable presser foot claw 18 and the similarly shaped bar 21 of the runner guide 20 adjustably mounted on said bar by means of the bored block 22 and adapted to be secured in various positions thereon by means of the set screw 23. It is also adjustably mounted on the block 22 by having its upwardly.

extending shank 24 running through a flat sided aperture 25 in the block, so that the set screw 26 will hold it in various positions to which it may be adjusted vertically. The bar 21 and shank 24 are flat sided to fit the holes 4 and 25 respectively, and be held thereby against turning.

The foot member 27 is secured to the other member of the presser foot by means of its shank 28 extending through and secured in the recess 3, so that the two when thus joined together form an ordinary presser foot with two claws or fingers and a needle slot 29 between them. The width of this slot, however, may be adjusted by moving the detachable foot member to the right or the left and securing it by means of the binding screw 17. The same is true when the foot member 18 is employed, and this may be done at all times when the hole 4 is not occupied by the bar 21 or some other mounting member. Thus, when the plate attachment 30' is used, and its shank 31 occupies the recess 3, the presser foot may be completed by means of the member 18 mounted in the hole 4, but when the bar 21 is in the hole 4 this cannot be done. Therefore, to provide for cases in which both the recess 3 and hole 4 are occupied, the detachable foot member 32 is mounted on the plate 30 by having the rear edge of the plate passed into its horizontal slot 33 and the two secured by the set screw 34. The advantage of the double presser foot is well known, but to employ a double presser foot in connection with extending guide plates such as 30—which may be of any desired width—and a guide runner either integral with said plate or in the form shown at 29, has the double advantage of securely holding and moving the material operated upon step by step and guiding the said material accurately as it passes beneath the needle to form an exactly uniform selvage or border of the folded material or of extra material. The lateral adjustment of the runner 20 enables the operator to use it with plates of various widths, according to the width of the selvage or folded seam to be stitched, and the vertical adjustment gives the operator the advantage of being able to raise or lower the guide plate to accommodate various thicknesses of material, regulate the pressure thereon beyond the stitching and bring its bottom edge parallel with the bottom of the presser foot when it is working close in. These advantages are important, particularly when folded selvages are being formed on heavy goods.

The ribbon or tape guide presser foot attachment 35 is useful where seams are to be taped, and in other operations where tapes or ribbons are applied. It is attached to the presser foot, like the other members, by means of its shank 36, has a spring ribbon slot 37, the tension of which can be regulated by means of the adjusting screw 38 passing through the free ends 39 and threaded into one of them, or ribbons of different weights accommodated. The ribbon is usually fed through the slot 37 from a spool and under the needle. This attachment has various uses, and may, if desired, be detachably mounted on plates such as 30.

The double attachment (Figs. 16 and 17) has its flat bar 40 passed through the recess 3 and is clamped by the screw 17 at any point intermediate its ends. It acts in manner similar to the plates 30 on either side of the presser foot, the plate 41 being inclined upwardly. It also has a runner 42 vertically adjustable in an upstand-

ing bracket 43 by means of the thumb nut 44 threaded on the horizontally extending post 45 and clamping the upwardly extending shank 46 between it and the bracket, which is substantially U-shaped in horizontal cross section and holds the runner 42 against oscillation in a vertical plane. The bracket 43' of the opposite end of the flat bar 41 and the threaded post 45' serve the same purpose as the corresponding parts. Between 40 and 41 is a space 46 forming an opening across this member coincident with the needle slot 29, so that the said slot is left clear and unobstructed for the reciprocation of the needle therein.

What I claim is:

1. A presser foot construction comprising a vertical shank, a foot member extending horizontally from the lower end of the shank, a recess in the upper face of the foot member adjacent said shank, a member mounted on said shank for vertical adjustment toward and from said recess and having a portion extending over and in proximity to said recess, means for securing said member in adjusted position, said shank having a bore therein extending from the exterior thereof to said recess, a pressure member mounted in said bore and movable to said recess, and a detachable foot member having a part insertable into said recess to be clamped therein by pressure of said pressure member.

2. A presser foot shank, a foot member extending from the lower part thereof, said foot member having a recess therein, an adjustable part mounted on said shank and having a portion extending over and in proximity to said recess, means for fixing said adjustable part in adjusted position on said shank, said shank having a bore therein extending from the exterior thereof to said recess, a pressure member mounted in said bore and movable to said recess, a member between said adjustable part and the bar and extending to said recess, a detachable foot member having a part insertable into the recess and arranged to receive pressure of said pressure member and to be clamped in said recess thereby.

3. A presser foot shank, a foot member extending from the lower part thereof, said foot member having a recess therein, an adjustable part mounted on said shank and having a portion extending over and in proximity to said recess, means for fixing said adjustable part in adjusted position on said shank, said shank having a bore therein extending from the exterior thereof to said recess, a pressure member mounted in said bore and movable to said recess, a member between said adjustable part and the bar and extending to said recess, and having a beveled portion in the path of said pressure member at the recess, a detachable foot member having a part insertable into the recess and arranged to receive pressure of said pressure member and to be clamped in said recess thereby through contact with said beveled portion which is interposed between them.

4. A presser foot shank, a foot member extending from the lower part thereof, said foot member having a recess therein, an adjustable part mounted on said shank and having a portion extending over and in proximity to said recess, means for fixing said adjustable part in position on said shank, said shank having a bore therein extending from the exterior thereof to said recess, a pressure member mounted in said bore and movable to said recess, a detachable foot

member having a part insertible into the recess and arranged to receive pressure of said pressure member and to be clamped in said recess thereby, said shank also having a lateral hole therethrough and a bore extending to and in communication with said hole, and a second presser foot member having a portion fitting said hole for mounting it upon the shank.

5. A presser foot shank, a foot member extending from the lower part thereof, said foot member having a recess therein, an adjustable part mounted on said shank and having a portion extending over and in proximity to said recess, means for fixing said adjustable part in position on said shank, said shank having a bore therein extending from the exterior thereof to said recess, a pressure member mounted in said bore and movable to said recess, a detachable foot member having a part insertible into the recess and arranged to receive pressure of said pressure member and to be clamped in said recess thereby, said shank also having a lateral hole therethrough and a bore extending to said hole, and a second presser foot member having a portion fitting said hole for mounting it upon the shank and a part of the means for fixing said adjustable part passing through said last named bore and constructed and arranged to engage and secure said second detachable foot member.

6. A presser foot shank, a foot member extending from the lower part thereof, said foot member having a recess therein, an adjustable part mounted on said shank and having a portion extending over and in proximity to said recess, means for fixing said adjustable part in adjusted position on said shank, said shank having a bore therein extending from the exterior thereof to said recess, a pressure member mounted in said bore and movable to said recess, a detachable foot member having a part insertible into the recess and arranged to receive pressure of said pressure member and to be clamped in said recess thereby, said detachable foot member extending laterally away from the first foot member, and a second presser foot member detachably mountable thereon.

7. A presser foot shank, a foot member extending from the lower part thereof, said foot member having a recess therein, an adjustable part mounted on said shank and having a portion extending over and in proximity to said recess, means for fixing said adjustable part in position on said shank, said shank having a bore therein extending from the exterior thereof to said recess, a pressure member mounted in said bore and movable to said recess, a detachable foot member having a part insertible into the recess and arranged to receive pressure of said pressure member and to be clamped in said recess thereby, said detachable foot member extending forward of said first foot member and having a tape guiding slot therein.

8. A presser foot shank, a foot member extend-

ing from the lower part thereof, said foot member having a recess therein, a detachable foot member having a part insertible into the recess and arranged to be adjustably secured therein,

5 6 said shank having a bore therein, a second detachable foot member having a portion adjustably held in said bore and extensible laterally beyond the first foot member, a guide runner forming a part of said second foot member vertically adjustable thereon and with respect to the foot member and the first detachable foot member.

10 9. A presser foot shank, a foot member extending from the lower part thereof, said foot member having a recess therein, an adjustable part mounted on said shank and having a portion extending over and in proximity to said recess, means for fixing said adjustable part in position on said shank comprising a pair of set screws out of line vertically and run through slots with 15 which said adjustable part is provided, said shank having a bore therein extending from the exterior thereof to said recess, a pressure member mounted in said bore and movable to said recess, a detachable foot member having a part insertible into the recess and arranged to receive pressure of said pressure member and to be clamped in said recess thereby.

20 10. A presser foot shank, a foot member extending from the lower part thereof, said foot member having a recess therein, an adjustable part mounted on said shank and having a portion extending over and in proximity to said recess, means for fixing said adjustable part in position on said shank, said shank having a bore therein 25 extending from the exterior thereof to said recess, a pressure screw threaded in said bore and movable to said recess, a detachable foot member having a part insertible into the recess and arranged to receive pressure of said pressure screw and to be clamped in said recess thereby, a bore running through said shank and a second detachable foot member having a portion adapted to be passed into said bore and secured therein at different positions.

30 11. A presser foot shank, a foot member extending from the lower part thereof, said foot member having a recess therein, an adjustable part mounted on said shank and having a portion extending over and in proximity to said recess, means for fixing said adjustable part in position on said shank, said shank having a bore therein extending from the exterior thereof to said recess, a pressure screw threaded in said bore and movable to said recess, a detachable foot member having a part insertible into the recess and arranged to receive pressure of said pressure screw and to be clamped in said recess thereby, a bore running through said shank and a second detachable foot member having a portion adapted to be passed into said bore and secured therein at different positions by a part of the means for fixing said adjustable part.

ABRAHAM MASLER.
